UNITED STATES PATENT OFFICE.

GEORGE DOBMEIER, OF BUFFALO, NEW YORK.

SAFETY-BUNG.

1,353,732.

Specification of Letters Patent. Patented Sept. 21, 1920.

Application filed September 26, 1919. Serial No. 326,550.

To all whom it may concern:

Be it known that I, GEORGE DOBMEIER, a citizen of the United States, residing in Buffalo, in the county of Erie and State of New York, have invented new and useful Improvements in Safety-Bungs, of which the following is a specification.

This invention relates to a safety bung for barrels, casks and the like in which pressure is developed as in the case of barrels containing cider, wine and the like, and thus automatically relieves excess pressure therein and prevents the barrel from bursting.

The object of this invention is to provide a safety bung for this purpose which is reliable in operation, capable of being used in connection with any of the standard forms of barrels or other receptacles and which can be produced at low cost and easily adjusted to relieve the pressure in a barrel at a predetermined point.

In the accompanying drawings:

Figure 1 is a vertical section of a safety bung embodying one form of my invention, the section being taken on line 1—1, Fig. 3. Fig. 2 is a side elevation of the same. Fig. 3 is a top plan view thereof. Figs. 4, 5, 6 and 7 are detached perspective views of the transverse retaining member, follower, body and annular band forming part of my invention.

Similar characters of reference refer to like parts throughout the several views.

10 represents the body of the bung which is preferably constructed of wood and has its periphery constructed of inwardly tapering form so that when driven into the bung hole 11 of the barrel or cask 12, or other receptacle intended to receive the same the body will be held therein by friction in the usual manner of holding bungs in place.

Extending lengthwise through the body is a passage, the inner or rear part 13 of which is comparatively narrow while the outer part 14 of the same is wide or enlarged forming an outwardly facing valve seat 15 which is preferably provided with a packing ring or gasket 16.

Arranged within the enlarged part of the passage and movable toward and from the seat is a valve 17, preferably in the form of a disk, for controlling the passage or port of the bung. This valve is yieldingly held against its seat by a spring 18 arranged in the enlargement 14 and bearing at its inner end against the outer side of the valve while

its outer end bears against the follower 19 preferably of disk form which is arranged in the outer part of the passage.

Across the outer end of the body and the follower is arranged a transverse retaining member which serves to hold the follower in place this member being preferably constructed of two parallel wires 20, 20 which are seated in a pair of transverse grooves 21 formed in the outer end of the body and also in a pair of transverse grooves 22 formed in the outer side of the follower, thereby holding these several parts against displacement relatively to each other in a direction perpendicular to the length of the retaining wires.

Around the outer part of the periphery of the body, is arranged a band 23 preferably of wire which is seated in an annular groove 24 in the body for confining this band in place on the body. The opposite ends of the retaining member are connected with diametrically opposite sides of the band in such manner that these parts may be detached to permit of removing the spring from the body and replacing the same by one of greater or less strength and thus permit of adapting the resistance of the valve to the pressure it is desired to maintain in the barrel. This detachable connection preferably consists of a loop 25 connecting two corresponding ends of the retaining wires 20 and passing around an ear 26 formed on the band by twisting together a portion of the wire from which this band is constructed while the opposite ends of these retaining wires are constructed to form hooks 27 which are passed around an ear 28 formed on the diametrically opposite part of the band by twisting together another part of the wire of this band, as shown in Figs. 1, 2, 3, 4 and 7.

When a bung of this construction is applied to the barrel the pressure will be held therein until the tension of the spring is exceeded and then the valve will be opened automatically and permit the excess pressure to escape, thus preventing the barrel from bursting. When pressure in the barrel has been again reduced to normal the valve is closed automatically by the spring without permitting any external air to enter the barrel, which otherwise might impair the contents of the barrel, but instead preserving the same in a pure condition.

A device of this character enables the con-

tents of the barrel to develop naturally and in the best condition without liability of losing the same or impairing its qualities as would be liable to occur if no safety means 5 were provided to relieve any excess pressure on the barrel.

I claim as my invention:

1. A safety bung comprising a body adapted to be placed in a bung hole and provided 10 with a longitudinal passage the inner part of which is narrow and the outer part wider forming an outwardly facing valve seat between the narrow and wide parts of said passage, a longitudinally movable valve arranged in the outer wide part of said passage and engaging said seat, a spring arranged on the wide part of said passage and engaging its inner end with said valve, a follower engaging with the outer end of 15 said spring, a retaining member arranged transversely on the outer end of said body and engaging said follower, and a band secured around the outer end of the periphery of said body and connected on diametrically 20 opposite sides with opposite ends of said retaining member.

2. A safety bung comprising a body adapted to be placed in a bung hole and provided with a longitudinal passage the inner part 30 of which is narrow and the outer part wider forming an outwardly facing valve seat between the narrow and wide parts of said passage, a longitudinally movable valve arranged in the outer wide part of said passage and engaging said seat, a spring arranged in the wide part of said passage and engaging its inner end with said valve, a follower engaging with the outer end of 35 said spring, a retaining member arranged transversely on the outer end of said body and engaging said follower, and a band secured around the outer end of the periphery of said body and connected on diametrically 40 opposite sides with opposite ends of said retaining member, the outer end of said body being grooved and forming a depressed seat for said retaining member.

3. A safety bung comprising a body adapted to be placed in a bung hole and provided 50 with a longitudinal passage the inner part of which is narrow and the outer part wider forming an outwardly facing valve seat between the narrow and wide parts of said passage, a longitudinally movable valve arranged in the outer wide part of said passage and engaging said seat, a spring arranged on the wide part of said passage and engaging its inner end with said valve, a 55

follower engaging with the outer end of said spring, a retaining member arranged 60 transversely on the outer end of said body and engaging said follower, and a band secured around the outer end of the periphery of said body and connected on diametrically 65 opposite sides with opposite ends of said retaining member, the outer part of the periphery of said body being provided with an annular groove which receives said band.

4. A safety bung comprising a body adapted to be placed in a bung hole and provided 70 with a longitudinal passage the inner part of which is narrow and the outer part wider forming an outwardly facing valve seat between the narrow and wide parts of said passage, a longitudinally movable valve arranged in the outer wide part of said passage and engaging said seat, a spring arranged on the wide part of said passage and engaging its inner end with said valve, a follower engaging with the outer end of 75 said spring, a retaining member arranged transversely on the outer end of said body and engaging said follower, and a band secured around the outer end of the periphery of said body and connected on diametrically 80 opposite sides with opposite ends of said retaining member, the outer end of said body and the outer side of said follower being grooved to receive said transverse retaining member.

5. A safety bung comprising a body adapted to be placed in a bung hole and provided with a longitudinal passage the inner part of which is narrow and the outer part wider forming an outwardly facing valve seat between the narrow and wide parts of said passage, a longitudinally movable valve arranged in the outer wide part of said passage and engaging said seat, a spring arranged on the wide part of said passage and engaging its inner end with said valve, a follower engaging with the outer end of 95 said spring, a retaining member arranged transversely on the outer end of said body and engaging said follower, and a band secured around the outer end of the periphery of said body and connected on diametrically 100 opposite sides with opposite ends of said retaining member, the outer part of the periphery of said body being provided with an annular groove which receives said band, and the outer end of said body being provided with a groove which receives said retaining member.

GEORGE DOBMEIER.
